DEVICE FOR RECORDING SOUND ON FILM

Filed Sept. 27, 1930

UNITED STATES PATENT OFFICE

HERMAN A. DE VRY, OF CHICAGO, ILLINOIS, ASSIGNOR TO Q. R. S.-DE VRY CORPORATION,
OF CHICAGO, ILLINOIS, A CORPORATION OF ILLINOIS

DEVICE FOR RECORDING SOUND ON FILM

Application filed September 27, 1930. Serial No. 484,751.

The invention relates generally to devices for recording sound. More particularly the invention relates to those devices which are operated electrically and are adapted to record or produce sound markings on sensitized motion picture film of the type that is used in apparatus for effecting the synchronous reproduction of light and sound effects.

The object of the invention is to provide a device of the aforementioned character which is comparatively simple in construction and operates in a novel and improved manner to record or produce a sound marking on the sensitized film. In general, this device comprises an incandescent lamp, the bulb part of which is opaque except for a minute slit in the tip end thereof. The lamp is adapted to be positioned with respect to feeding or winding mechanism for the film so that the beam of light emanating from the slit strikes against one of the side margins of the film and forms on the film, as the latter is driven by the feed mechanism, an exposed portion of strip-like conformation.

The base of the lamp is connected to an electrically actuated vibrating unit which is associated with an electric circuit or system of the type that includes a microphone and produces current impulses that correspond to the waves or vibrations of the sound that is to be recorded and later produced. The aforesaid unit, when operated, vibrates the lamp differentially and correspondingly to the current impulses with the result that the beam of light radiating from the lamp exposes the marginal part of the film in such a manner that said part, when the film is developed, embodies a zigzag or jagged marking, the pointed parts of which vary in length and spacing in accordance with the magnitude and rapidity of the lamp-vibrations and serve as an accurate record of the sounds that are transmitted to the microphone of the electrical circuit or system for the vibrating unit.

The invention consists in the several novel features which are hereinafter set forth and are more particularly defined by the claims at the conclusion hereof.

In the drawings which accompanies and

forms a part of this specification or disclosure and in which like numerals of reference denote corresponding parts throughout the several views:

Figure 1 is a diagrammatic view of a sound recording device embodying the invention;

Figure 2 is an enlarged sectional view of the electrically actuated vibrating unit for the incandescent lamp;

Figure 3 is a view, partly in section and partly in elevation, of the lamp for making the sound record on the film;

Figure 4 is a bottom view of the lamp; and

Figure 5 is a perspective of a developed film that has been subjected to the action of the sound recording device.

The device which forms the subject matter of the present invention is adapted primarily for use in recording sound on a sensitized film *f* of the type that is used in cinematographs and has punched or otherwise formed in the side margins thereof holes *f'* for receiving the teeth of sprocket wheels or like driving elements. Said device comprises an incandescent sound recording lamp 5 which consists of a base 6 and a glass bulb 7. The base of the lamp has one end thereof joined to the bulb. The other end of the base is provided with a reduced stem 8. The bulb 7 is cylindrical with the exception of the outer or tip portion 7^a which embodies a pair of walls 7^b. The latter converge and join each other in a straight edge 7^c. In addition to the bulb and base, the lamp comprises a filament 9, the major or operative portion of which is disposed in the bulb 7. One end of the filament extends through the base and stem and is grounded in any suitable manner. The other end of the filament 9 projects through the side part of the base and is adapted to be connected by a flexible electrical conductor 10 to a source of electric current having a constant voltage. The lamp 5 is positioned adjacent a pair of sprocket wheels 11 and 12. The latter are adapted to support the film *f* so that one of the marginal parts thereof engages the edge 7^b of the bulb, and operate, during drive thereof, to feed the film longitudinally and relatively to the lamp. The sprocket wheel 12 is driven

100

by a gear 13 which meshes with a pinion 14 and is fixedly secured to the spindle or shaft that supports the sprocket wheel 12. The sprocket wheels 11 and 12, together with the lamp 5, are housed in a chamber 15 which is formed by any suitable housing structure and is closed against the admission of light.

The bulb 7 of the sound recording lamp is completely opaque except for a minute slit 16 which is positioned adjacent and is substantially equal in length to the edge 7^a and permits a relatively small and narrow beam of light to radiate from the lamp and strike against the film. The bulb is rendered opaque by plating the outer face thereof with chromium or a similar material so as to form an outer shell 17. The slit 16 is made by grinding away the part of the chromium shell that is positioned adjacent the edge 7^a.

The sound recording device comprises, in addition to the lamp 5, an electrically actuated unit 18. This unit supports the lamp and is adapted, as hereinafter described, to vibrate the same transversely with respect to the film. As a result of such vibrations of the lamp, the beam of light emanating from the aperture 16 moves back and forth in a sidewise direction and exposes the film, during operation of the sprocket wheels 11 and 12, in such a manner that the film, when developed, has formed thereon an elongated longitudinally extending marking f², one side of which is smooth and the other side of which is zigzag or jagged as illustrated in Figure 4.

An arm 19 serves to hold the unit 18 so that the latter supports the lamp in the proper position with respect to the film. This arm 19 is preferably so connected or positioned within the structure which forms the chamber 15, that the slit 16 of the lamp engages the film f slightly inwardly of one of the series of apertures f¹ and extends transversely with respect to the film. The unit 18 is similar in construction to the ordinary electric "pick-up" which is used in connection with phonographs of the electric reproducing type. It comprises a horse-shoe magnet 20. The latter is carried by and insulated from a supporting member 21 which is connected by a bracket 22 to the distal end of the arm 19. A pair of U-shaped pole pieces 23 and 24 are secured to the end parts of the magnet 20 and are so arranged that the legs thereof extend inwardly in parallel relation. A solenoid 25 is disposed between the legs of the pole pieces 23 and 24 and is insulated from the latter by strips 26 and 26^a of insulation. An elongated holder-element 27 extends through the solenoid 25 and is provided at its lower end with a socket 28. This socket is shaped so as to receive the stem 8 of the sound recording lamp and is provided with a thumb screw 29 for securing the lamp in place. The holder-element 27 is also provided at its lower end with a transversely extending member 30

which is provided with knife edges 30^a that bear against a plate 31 and operate together as a pivot whereby the holder-element 27 may be oscillated or shifted back and forth between the pole pieces 23 and 24. The plate 31 is positioned between the lower legs of the aforesaid pole pieces and the strip 26^a. The holder-element 27 is held against longitudinal displacement by a clamping-member 32 which is mounted on bolts 33 and is provided with a seat 34. A pad 35 is held in the seat 34 and engages the under part of the transversely extending member 30. This pad is formed of rubber or similar resilient material and permits the desired tilting or pivoting of the element 27. The clamping-member 32 is provided with a hole 36 through which extends the socket 28 of the holder-element. The bolts 33 are anchored to the supporting plate 21 and depend therefrom.

The ends of the wire which forms the solenoid 25 are connected respectively to a pair of conductors 37 and 38. The latter are adapted to be included in and to form a part of an electric circuit or system of the type that includes a microphone and produces current impulses that correspond to the waves or vibrations of the sound that is to be recorded. The electrical impulses which are transmitted to and pass through the conductors 37 and 38 cause the solenoid 25 to operate in such a manner that the holder-element vibrates between the pole pieces 23 and 24. This vibratory action of the element 27 is in turn imparted to the recording lamp 5 and results in a back and forth movement of the beam of light that emanates from the aperture 16. Since the sprocket wheels 11 and 12 are adapted to feed the film during operation of the unit 18, the beam of light from the lamp exposes the film so that when the latter is developed, it has on one margin thereof and from one end to the other the aforementioned zigzag or jagged marking f². In view of the fact that the electric impulses vary in intensity and number per a given unit of time according to the waves or vibrations of the sound that is transmitted to the microphone of the circuit for the unit 18, the vibrations of the holder-element 27 vary correspondingly in timing and magnitude. As a result of this condition or action, the beam of light emanating from the aperture 16 moves back and forth different distances and at different intervals, and consequently records the sound vibrations accurately on the film by way of the zigzag or jagged parts of the marking which are correspondingly of different length and width. The holder element 27 is preferably arranged so that it is shifted back and forth from a fixed position by the electrical impulses which are transmitted to the conductors 37 and 38. As a result of this arrangement, the lamp returns after each vibration to a fixed position and causes one edge of the

marking on the film to be made in the form of a straight line, as indicated in Figure 5.

Assuming that the film *f* is being fed by the sprocket wheels 11 and 12 and that the lamp 5 is illuminated by virtue of the flexible conductor 10 being connected to a source of current, the operation of the sound recording device will be as follows:

The electrically actuated vibrating unit 18 will be subjected to electrical impulses corresponding in magnitude and number to the waves of the sound that is to be recorded. These impulses operate as previously described to vibrate differentially the holder-element 27 and the lamp. The beam of light radiating from the lamp through the aperture 16 strikes against the moving strip of film and by reason of the fact that it is oscillated or moved back and forth responsively to the action of the unit 16, it exposes the film so that the latter, when developed, has an accurate zigzag or jagged sound marking thereon. Upon completion of the sound recording operation and the development of the film *f*, said film may be used in any suitable apparatus for effecting the synchronous reproduction of light and sound effects. In view of the fact that the edge 7^c of the lamp 5 engages or is in close proximity to the film during the recording operation, the only portion of the film which is exposed is the portion against which the beam of light strikes.

The sound recording device herein disclosed consists of but a small number of parts and consequently may be manufactured at a comparatively low cost. It is extremely efficient, as far as operation is concerned, and may be operated economically.

The invention is not to be understood as restricted to the details set forth, since these may be modified within the scope of the appended claims, without departing from the spirit and scope of the invention.

This application is a continuation in part of an application filed by me June 26, 1929, Serial No. 373,821.

Having thus described the invention, what I claim as new and desire to secure by Letters Patent, is:

1. A device for recording sound markings on a light sensitive moving picture film, comprising in combination a unit adapted to be connected to an electrical system which produces current impulses corresponding to the waves or vibrations of the sound that is to be recorded, and embodying a vibrating element that is actuated by such impulses; means for feeding the film relatively to the unit; and a lamp connected to and vibrated by the element, said lamp being so arranged that when the unit and feed means are operated the light emanating from said lamp strikes against the film and exposes thereon a substantially zigzag or jagged marking.

2. A device for recording sound markings on a sensitized moving picture film, comprising in combination a unit adapted to be connected to an electrical system which produces current impulses corresponding to the waves or vibrations of the sound that is to be recorded, and embodying a vibrating element that is actuated by such impulses; means for feeding the film relatively to the unit; and a lamp connected to and vibrated by the element, the bulb of said lamp being opaque except for a minute aperture and being so arranged that when the unit and feed means are operated the beam of light emanating from said aperture strikes against the film and exposes thereon a substantially zigzag or jagged marking.

3. A device for recording sound markings on a sensitized moving picture film, comprising in combination a unit adapted to be connected to an electrical system which produces current impulses corresponding to the waves or vibrations of the sound that is to be recorded, and embodying a vibrating element that is actuated by such impulses; means for feeding the film relatively to the unit; and a lamp connected to and vibrated by the element, the bulb of said lamp being provided with an apertured opaque shell and being so arranged that when the unit and feed means are operated the beam of light emanating from the aperture in the shell strikes against the film and exposes thereon a substantially zigzag or jagged marking.

4. A device for recording sound markings on a sensitized moving picture film, comprising in combination a unit adapted to be connected to an electrical system which produces current impulses corresponding to the waves or vibrations of the sound that is to be recorded, and embodying a vibrating element that is actuated by such impulses; means for feeding the film relatively to the unit; and a lamp connected to and vibrated by the element, the bulb of said lamp being rendered opaque by a metallic plating having an aperture therein, and being so arranged that when the unit and feed means are operated the beam of light emanating from the aperture strikes against the film and exposes thereon a substantially zigzag or jagged marking.

5. A device for recording sound markings on a light sensitive moving picture film, comprising in combination a unit adapted to be connected to an electrical system which produces current impulses corresponding to the waves or vibrations of the sound that is to be recorded, and embodying a vibrating element that is actuated by such impulses; means for feeding the film relatively to the unit; and a lamp connected to and vibrated by the element, the bulb of said lamp being opaque except for a minute slit in one end thereof and being so arranged that when the unit and feed means are operated the beam of

light emanating from said slit strikes against the film and exposes thereon a substantially zigzag or jagged marking.

6. A device for recording sound markings on a sensitized moving picture film, comprising in combination a unit adapted to be connected to an electrical system which produces current impulses corresponding to the waves or vibrations of the sound that is to be recorded, and embodying a vibrating element that is actuated by such impulses; means for feeding the film relatively to the unit; and a lamp connected to and vibrated by the element, the bulb of said lamp being provided with a slotted opaque shell being so arranged that when the unit and feed means are operated the beam of light emanating from the slit in the shell strikes against the film and exposes thereon a substantially zigzag or jagged marking.

7. A device for recording sound markings on a sensitized moving picture film, comprising in combination a unit adapted to be connected to an electrical system which produces current impulses corresponding to the waves or vibrations of the sound that is to be recorded, and embodying a vibrating element that is actuated by such impulses; means for feeding the film relatively to the unit; and a lamp connected to and vibrated by the element, the bulb of said lamp being shaped at one end thereof to form an edge, embodying therearound an opaque shell having a slit adjacent the edge and being so arranged that when the unit and feed means are operated, the beam of light emanating from the slit strikes against the film and exposes thereon a substantially zigzag or jagged marking.

Signed at Chicago, Illinois, this 23rd day
of September, 1930.
